(57) **CLAIM**

(21) Appl. No.: **29/498,840**

The ornamental design for a combustion engine exhaust for snowmobiles and all terrain vehicles, as shown and described.

(22) Filed: **Aug. 8, 2014**

DESCRIPTION

(51) LOC (10) Cl. **12-16**

FIG. 1 is a front perspective view showing my new design for a combustion engine exhaust for snowmobiles and all terrain vehicles;

(52) U.S. Cl.

FIG. 2 is a right side elevational view;

USPC **D12/194**

FIG. 3 is a top plan view;

(58) **Field of Classification Search**

FIG. 4 is a bottom plan view;

USPC D12/194; D15/1, 5

FIG. 5 is a front elevational view;

CPC F01N 13/10; F01N 3/2892

FIG. 6 is a left side elevational view;

See application file for complete search history.

FIG. 7 is a rear elevational view; and,

(56) **References Cited**

FIG. 8 is a side elevational view of the exhaust on a combustion engine in phantom broken lines.

U.S. PATENT DOCUMENTS

The broken line drawings of the combustion engine are for illustrative purposes only and form no part of the claimed design.
